UNITED STATES PATENT OFFICE.

THOMAS S. HOMANS, OF HEMPSTEAD, NEW YORK, ASSIGNOR TO INTERNATIONAL
TYPESETTING MACHINE COMPANY, OF NEW YORK, N. Y., A CORPORATION OF NEW
YORK.
MATRIX-MAGAZINE FOR TYPOGRAPHICAL MACHINES.

1,142,758.

Specification of Letters Patent. Patented June 8, 1915.

Application filed February 19, 1914. Serial No. 819,754.

To all whom it may concern:

Be it known that I, THOMAS S. HOMANS, a citizen of the United States, residing at Hempstead, in the county of Nassau and State of New York, have invented new and useful Improvements in Matrix-Magazines for Typographical Machines, of which the following is a specification.

My present invention relates to improvements in typographical machines and more especially to those of the linotype class wherein the matrices from which the lines of type are cast are stored in a magazine.

It is customary to place such magazines in an inclined position on the machines, the upper end of the magazine being normally open to receive matrices from the distributing mechanism and the lower end of the magazine having means for delivering the matrices to the matrix assembling mechanism. At times it is desirable to remove a magazine from the machine and to substitute another magazine containing a different font of matrices, and in doing this the magazine is liable to become inverted or tilted. Hence, it is desirable to provide the magazine with means to prevent accidental escape or spilling of the matrices from the upper or matrix-receiving end thereof.

The primary objects of the present invention are to so construct the magazine as to provide means which will prevent the escape of matrices therefrom, such means being contained within the length of the magazine and having no projecting parts to increase such length, thereby avoiding interference with the distributing mechanism, and to facilitate and cheapen the manufacture of the magazine.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a perspective view of the upper right-hand corner of a magazine constructed in accordance with the present invention; Fig. 2 represents a longitudinal section of the same in partially inverted position; Fig. 3 is a view of the upper right-hand corner of

the magazine with the upper plate thereof removed.

Similar parts are designated by the same reference characters in the several views.

The present invention is shown by way of example as applied to matrix-containing magazines of the type generally employed in connection with typographical machines of the linotype class.

It will be understood, however, that the invention is not restricted to the precise construction shown, as equivalent constructions within the scope of the claims at the end of the specification may be used and will be included thereby.

The magazine, as shown, comprises top and bottom plates 1 and 2 which are spaced to accommodate the matrices in edgewise position between them. The inner faces of the plates 1 and 2 are grooved to form channels 3 and 4 which receive the upper and lower ears on the matrices and thereby guide the latter. In the normal position of the magazine on the machine the inclination of the magazine is sufficient to cause feeding of the matrices by gravity to the lower or delivery end thereof, it being customary to control the delivery of matrices from the lower end of the magazine by escapement devices which are well known in this art.

It is customary in machines of this class to provide distributing mechanism for returning the matrices, after a cast has been made, to the upper end of the magazine, the matrices dropping into the appropriate channels. The distributing mechanism usually embodies screws which feed the matrices across the upper end of the magazine with the matrices spaced apart a distance greater than the distance between the matrix channels in the magazine, and in order to insure the proper entrance of the matrices into their appropriate channels in the magazine the upper ends of the matrix-receiving channels are usually flared or widened, as at 5 in Fig. 3. In manufacturing magazines wherein the matrix-receiving channels are flared or widened at their upper ends, difficulty is experienced in forming the flared or widened portions of the channels where the widened portions thereof are formed on the same plates which constitute the body of the magazine, owing to the necessity of in-

terrupting the action of the cutting tools which flare or widen the channels before such tools strike the opposite sides or walls of the channels, it being understood that 5 the cutting tools which widen or flare the channels operate at an angle to the length of the straight and relatively long channels.

According to the present invention, this difficulty is avoided by forming the widened 10 or flared portions of the channels in plates 1^a and 2^a which are separate from the plates 1 and 2 although they practically form continuations of those plates, and the total length of the magazine is the same as where 15 the flared or widened portions of the channels are formed in integral parts of the top and bottom plates of the magazine. By forming the flared or widened portions of the channels in separate plates, the operation 20 of producing the same is obviously facilitated and cheapened as the cutting tools may move across the separate plates without injury to any part of the magazine. By so constructing the magazine, the plates 25 1^a and 2^a can be utilized as locks to prevent escape of matrices from the upper end of the magazine when the same is inverted. To accomplish this, the plates 1^a and 2^a are mounted on hinge pins 6 and 7, these hinge 30 pins being supported by hinge members 8 which may be fastened at suitable intervals to the plates 1 and 2 of the magazine, the complementary hinge members 9 being secured to the upper and lower sides of the 35 plates 1^a and 2^a respectively.

When the magazine is in operative position, the plates 1^a and 2^a are in alignment with and form substantially unbroken continuations of the plates 1 and 2 of the magazine, thus affording an unobstructed opening 40 through which the matrices may pass from the distributing mechanism into the appropriate channels of the magazine. The plates 1^a and 2^a are shown in such position 45 in Fig. 1 of the drawing.

When it is desired to remove the magazine from the machine, the plates 1^a and 2^a are moved toward one another and they will then prevent the escape of any matrices 50 from such end of the magazine, it being understood that the plates 1^a and 2^a extend across the upper end of the magazine whereby they will control all the matrix channels thereof. Fig. 2 shows the plates 1^a and 2^a 55 in a position to prevent escape of the matrices.

Means is provided by the present invention for retaining the plates 1^a and 2^a either in normal position to permit matrices to 60 enter the magazine or in a position to prevent the escape of matrices.

In the construction shown, the end hinge members 9 at both sides of the magazine are provided with projections 10, and catches 65 11 are pivoted on pins or screws 12 on the

top and bottom plates 1 and 2 whereby these catches will swing laterally. When the magazine is in normal position on the machine, the catches 11 will engage between the projections 10 and the plates 1^a and 2^a respectively 70 and will thereby hold said plates in alignment with the channeled plates 1 and 2 of the magazine. When the magazine is to be removed from the machine, the catches 11 are released and then brought into position 75 to engage above and below the projections 10 on the plates 1^a and 2^a respectively, as shown in Fig. 2, said plates being then held in positions to prevent the escape of matrices.

Springs 13 are shown for retaining the 80 catches 11 in either of the positions mentioned, and the side plates 14 at each side of the magazine and which serve to hold the plates 1 and 2 in proper spaced relation are notched as at 15 to permit the plates 1^a and 2^a 85 to swing toward one another, as shown in Fig. 2.

By so constructing the magazine, the manufacturing of the magazine is facilitated and cheapened and, furthermore, the length 90 of the magazine is not increased as the plates containing the flared or widened portions of the channels are parts of the main channeled plates, and by movably mounting the plates containing the widened portions of the channels, simple and efficient means is provided 95 for preventing escape of matrices when the magazine is partially or completely inverted.

I claim as my invention:—

1. A matrix magazine composed of opposite plates having normally continuous matrix-guiding channels, the entrance ends of which plates are relatively movable to break the continuity thereof and thereby prevent the escape of matrices. 100

2. A matrix magazine composed of opposite plates having portions provided with matrix-guiding channels, said plates having relatively movable parts provided with channel entrances continuous with said channels when in one position, said parts being movable into positions to break the continuity of said channels and thereby prevent escape of matrices from the magazine when the latter is partially or completely inverted. 105 110

3. A matrix magazine having a pair of opposed plates formed with straight matrix-guiding grooves, and one or more relatively movable plates formed with flared or widened grooves and adapted to form continuations of or interruptions to said straight grooves. 115 120

4. A matrix magazine having relatively fixed plates formed with straight matrix-guiding grooves and having a pair of pivoted plates formed with flared entrances for said grooves and movable toward and from one another to form continuations of or interruptions to said grooves. 125

5. A matrix magazine having opposite 130

grooves for guiding the projecting lugs or ears of the matrices, the upper or entrance ends of said grooves being tapered outwardly and formed in separate portions 5 movably mounted on said magazine.

In testimony whereof I have hereunto set

my hand in presence of two subscribing witnesses.

THOMAS S. HOMANS.
